PAD

Morris Felick, Chicago, Ill.

Application July 27, 1944, Serial No. 546,819

1 Claim. (Cl. 2-268)

The present invention relates to improvements in garment construction, and more particularly to a novelly constructed pad to be applied to a garment for squaring off the shoulders and such other parts of the garment which, when in use, hang over that area of the wearer's back in the region of the scapula.

It is well known that garments, such as coats, usually are provided with shoulder pads so as to square off the shoulders and thereby improve the fit and hang of the garment when it is worn. Common practice, however, is to prefabricate pads in a wide range of sizes and shapes and to leave it entirely to the workman constructing the garment to select a size and shape thought to suit the particular garment. Such prefabricated pads are of predetermined thicknesses and of sizes that underlie the shoulder portions of the garment only. Thus, even when a pad of proper thickness is arranged in a garment, the garment, when worn, may sag where it hangs across the scapula areas of the body, thus emphasizing the customary hollow in those areas and often causing the back of the garment to appear wrinkled and drawn. Heretofore, such unsightly appearance has been partially overcome only by refitting the garment to the individual by whom it is to be worn, and even then the garment will hang taut and flat across such areas.

It is therefore an object of the invention to construct a garment in such manner that when worn the entire back areas will present a smooth, fully rounded appearance.

Frequently it is desirable, and often necessary, even when using the prefabricated pads of the present invention, to vary the thickness of certain areas of the pad so as to conform to the individual characteristics of a hollow in the back area, the appearance of which it is intended to eliminate. Accordingly, it is another object of this invention to provide a pad of the kind described hereinabove, with a pocket for receiving an insert of selected size so as to effect easy and simple variation in the pad thickness.

Pads constructed along present lines usually consist of an outer covering having a filler of wool or cotton. Obviously such pads easily lose their original configuration, primarily because such a filler does not retain its initial resiliency after a period of use. As a result, it early becomes compressed or wadded, and thereby assumes a different shape from that required to retain the initial appearance of the garment. It is therefore another object of the invention to provide a pad of the character described with

an insert filler of a kind which will retain its resiliency and consequently its intended shape throughout the serviceable life of the garment.

Other and further objects of the present invention will be apparent from the following description and claims, and are illustrated in the accompanying drawing which by way of illustration shows a preferred embodiment and the principle thereof, and which is considered to be the best mode contemplated for applying that principle. Other embodiments of the invention, embodying the same or equivalent principle, may be used and structural changes may be made as desired by those skilled in the art without departing from the present invention and the purview of the appended claim.

In the drawing:

Fig. 1 is a fragmentary rear elevational view of a garment embodying features of the present invention, showing a portion of the back broken away.

Fig. 2 is a side elevational view of the garment partially broken away.

Fig. 3 is an elevational view of the pad showing portions thereof broken away.

Fig. 4 is a side elevational view of the pad shown in Fig. 3.

Fig. 5 is a sectional detail view taken on the line 5-5 of Fig. 3.

Fig. 6 is a diagrammatic view illustrating the location of the pad with respect to the wearer's body.

The pad 10 of the present invention consists of a pair of identically shaped pieces of covering material 11 which are arranged in superimposed relation and joined together along complementary edges as by rows of stitches 12. As best illustrated in Fig. 3, the rows of stitches extend over the entire curved edges of the pieces of material 11, and the straight edges 13 are left free. The pieces of material 11 preferably are fashioned from buckram or other suitable substantially stiff, shape retaining fabric. A layer of batting 14, such as cotton, is arranged on the inside face of each piece of material 11 and said batting is shaped to conform to the contour of said sheets and is held in place by the rows of stitches 12.

Upon reference to Fig. 4, it will be noted that the opposed layers of batting 14 may be spread apart along the open edge 13 of the covering 11 so as to provide in effect a pocket, generally indicated at 15, into which a suitable filler insert 16 may be positioned. The filler insert 16 preferably is made up of steel wool, but obviously it

may be formed of any other suitable material, such as for example kapok or the like, and it may be of such shape as is required to give the finished pad the required thickness. One face of the pad is provided with a suitable covering sheet 11, preferably of flannel or other soft material, which sheet has its margins 18 along the curved edges of the pad extending outwardly beyond said edges a slight distance for a purpose to be better understood as the description proceeds. The covering sheet 11 may be secured to the pad by the rows of stitches 12 or it may be attached thereto by independent stitching.

The pad described hereinabove has been shown as applied to a garment 19 consisting of a back 21 having armholes 22 into which sleeves 23 are stitched in the usual and customary manner. As best illustrated in Figs. 1 and 2, one pad 10 is applied to the inside of the garment adjacent each armhole 22 in such position that the open 18 or straight edge 13 of the pad lies adjacent to and follows the seam of the said armhole. The portion of the pad containing the insert filler 16 is superimposed against the inside face of that portion of the back 21 which overlies the back of 20 the wearer in the region of the scapula.

As is well known, this region of a person's back is substantially hollow or depressed and it is a purpose of the present invention to so arrange the pad that the hollow is not apparent when the garment in which the pad is arranged is being worn. Accordingly the positioning of the pad, as described hereinabove, is such that the hollow is substantially filled out so that the garment will have a smart, well fashioned appearance while being worn, and at the same time the shoulders of the garment will square off. This squaring off of the shoulders is accomplished by superimposing the uppermost or smaller portion of the pad 10 against the inside face of the top of the shoulder, as best illustrated in Fig. 6.

The garment 19 preferably is provided with the usual lining 24 which when secured in place overlies and completely conceals the pads. Inasmuch as the lining material commonly used in garments is easily damaged or worn by friction, the pads 10 are so arranged in the garment as to dispose the faces thereof having the soft covering 17 towards the lining. The extended margin 18 of said soft covering adequately prevents the complementary edge of the buckram material 11

from coming into contact with the lining and further provides means whereby the pad may be blind-stitched to the back of the garment should such stitching be required or desirable.

5 It should be evident from the foregoing that applicant has provided a garment wherein the shoulders and portions of the back are suitably padded so as to prevent the garment from sagging, wrinkling, or appearing drawn where it lies over the region of the scapula while being worn and that such pads may be readily varied in thickness so as to be easily fitted into hollows of various degrees without extensive or customary alteration of the garment.

10 It should be understood further that the specific shape and form of the pad illustrated may be varied to suit various conditions of garment manufacture, without departing from the spirit of this invention or the scope of the appended claim.

I claim:

15 The combination with a lined garment comprising a back portion, a shoulder portion and a sleeve stitched to said portions, of a pad superimposed on the inside face of the shoulder and back portions adjacent the armhole of said sleeve, said pad comprising a pair of like pieces of material of such size and shape as to overlie a selected area of the back portion adjacent to the sleeve, said pieces of material being straight on one complementary edge and having rows of stitches joining their remaining edges; a similarly shaped layer of filler material arranged on the inside face of each piece of material and secured in place 20 by said rows of stitches, said pieces of material and layers of filler material being unsecured along their complementary straight edges so as to provide a pocket adapted to have its mouth disposed at the armhole of the sleeve, a filler of selected size and shape contained in said pocket, and a covering sheet of soft material on one face of the pad secured thereto by said rows of stitches, said covering sheet being of a shape similar to that of the pad and having its margins extending in the plane of the pad beyond the stitched edges only so as to protect the garment lining from injury by rubbing contact with said pieces of material or with said stitched edges, the margins also affording means for blind stitching the pad to the garment.

25 MORRIS FELICK.
